JOHN E. KALGREN, OF MINNEAPOLIS, MINNESOTA, ASSIGNOR TO J. R. CLARK COMPANY, OF MINNEAPOLIS, MINNESOTA, A CORPORATION OF MINNESOTA.

IRONING BOARD.

Application filed June 16, 1922. Serial No. 568,807.

The object of my invention is to provide an ironing board of comparatively simple, inexpensive construction and at the same time firm and rigid when set up and in use. 5 The invention consists generally in various constructions and combinations, all as hereinafter described and particularly pointed out in the claims.

In the accompanying drawings forming 10 part of this specification,

Figure 1 is a side view of an ironing board embodying my invention,

Figure 2 is a bottom view of the board folded,

15 Figure 3 is a detail sectional view showing the yielding button between the legs and the bottom of the board,

Figure 4 illustrates the manner of engaging the brace between the end legs and the 20 bottom with the underside of the board.

In the drawing, 2 represents the ironing board top. 3 is a bracket, preferably of metal, secured to the top on the underside and having depending ears 4. 5 represents

25 end legs pivotally connected at 6 to the ears 4 and having cross bars 7 and 8 between the legs and diagonal braces 9 connecting the middle point of the cross bar 8 with the legs adjacent the ends of the bar 7. Rails 10 are

30 arranged in parallel relation and secured to the cross bars 7 and 8 and a brace 11 is pivotally connected at 12 to the rails 10 and has a beveled end 12^a to fit against the underside of the board and the beveled surface 13 of a

35 block 14 that is secured to the board. A third leg composed of rails 15 having their end portions mounted on the same pivot bolts as the legs 5 projects beyond the bar 3 and has beveled surfaces 16 for contact with

40 yielding buttons 17 which are secured to the underside of the top. At the opposite end these rails 15 have a block 18 to contact with the floor. A cross pin 19 is mounted in the rails 15 and when the board is set up, this

45 pin is adapted to enter a notch 20 provided in the edge of the brace 11, thereby locking the parts securely together and resisting downward pressure and preventing the tilting and twisting of the boards, which so

50 often occurs in articles of this type as ordinarily constructed. The buttons yield as the board is set up, take up all lost motion in the parts and insure a rigid substantial frame for the board.

I claim as my invention:

1. An ironing board comprising a top, and 55 end legs pivotally connected to the under side of the top, a middle leg composed of rails pivotally connected at their upper ends to the under side of the top concentric with the pivots of said end legs, yielding bearings for the middle leg on the under side of said top adjacent said pivots, the lower ends of said middle leg rails being secured together and having a bearing upon the floor, a brace 60 pivotally connected at its lower end with the middle portion of said end legs and having its upper end adapted to bear against the under side of said top, and the middle of 65 said brace and the corresponding portion of said middle leg having means for interlocking when the parts are in operative position and being separable by downward movement of the upper end of the brace.

2. An ironing board comprising a top, end 70 legs pivotally connected to the underside of said top near one end, a middle leg composed of rails pivotally connected at their upper ends to the underside of said top concentric with the pivots of said end legs, the lower ends of said middle leg rails being secured together 75 and having a bearing upon the floor and a brace pivotally connected at one end with the middle portion of said end legs and having an opposite end adapted to bear 80 on the underside of said top, the middle portion of said brace having an upwardly opening notch therein and the rails of said middle leg having a pin extending between them 85 that is adapted to enter the notch in said brace when the board is set up.

3. An ironing board comprising a top, a leg pivotally connected to the under side of the top adjacent one end, a rail leg pivotally connected to the under side of said top and having an end for contact with the top, cushion means between the last named end and the top adapted to be under compression when the rail leg is in supporting 95 position, a brace pivotally connected at one end with said end leg and having a detachable locking engagement with the board, said brace having an intermediate notch, and said rail leg having a pin adapted to enter the notch when the board is set up.

4. An ironing board comprising a top, a strap secured to the under side thereof near one end and having depending ends, a mid-

dle leg composed of rails pivotally connected at one end to the depending ends of said strap and having their opposite ends secured together, end legs having their upper ends pivotally connected to the depending ends of said strap concentric with the pivots of the rails of said middle leg, said end legs having rails between them, yielding buttons interposed between the upper ends of the rails of said middle leg and the under side of said top, a cross pin between the rails of said middle leg, a brace pivotally connected

at one end with the rails of said end legs and having an upper end to engage the under side of said top and fitting against a cross bar thereon, the middle portion of said brace having a notch therein to receive said cross pin, the engagement of said brace with said top and said cross pin operating to compress the yielding means. 15

20 In witness whereof, I have hereunto set my hand this 9th day of June, 1922.

JOHN E. KALGREN.
